UNITED STATES PATENT OFFICE.

PAUL CORNELIUS, OF BERLIN, GERMANY.

SMOKE-CONSUMING FURNACE.

SPECIFICATION forming part of Letters Patent No. 613,359, dated November 1, 1898.

Application filed December 30, 1897. Serial No. 664,535. (No model.)

To all whom it may concern:

Be it known that I, PAUL CORNELIUS, a subject of the German Emperor, residing at Berlin, in the Empire of Germany, have invented 5 certain new and useful Improvements in or Relating to Smoke-Consuming Furnaces, as set forth in the following specification.

I provide the furnace for a steam-boiler or for other purposes with an arrangement comprising 10 heating-pipes laid in the smoke-chamber, flues and channels leading to the chimney, a blower or compressor for sucking in the heated air and delivering it under a pressure to the fire, means for actuating said blower or compressor, a device for injecting 15 liquid or gaseous fuel or superheated steam into the compressed and heated air, and a series of hollow and perforated pipes or boxes or channels replacing the common fire-bars 20 either wholly or partly.

The objects of my invention are, first, to enable the mixture of heated air and liquid or gaseous fuel or superheated steam to penetrate even a high layer of burning and glowing 25 coals intermixed with slag-cinders; second, to increase the temperature of the fire, and thus to promote the combustion of the coal; third, to consume the smoke and attain 30 a complete consumption of the coal, and, fourth, to utilize even low-grade coal.

The arrangement is shown on the accompanying drawings, in which—

Figure 1 is a ground plan of a steam-boiler plant assumed to be provided with the new arrangement; Fig. 2, a vertical cross-section of same, taken on the line $y z$ in Fig. 1; Fig. 3, a cross-section of a fire-grate assumed to consist entirely in perforated pipes; Fig. 4, a cross-section of a fire-grate assumed to consist entirely in perforated boxes or channels; Fig. 5, a cross-section of a fire-grate assumed to consist partly in common fire-bars and partly in perforated pipes; Fig. 6, a vertical longitudinal section of a fire-grate, showing 45 a perforated pipe in its elevation; Fig. 7, a ground plan of a fire-grate, of which Fig. 5 is a cross-section on an enlarged scale; Fig. 8, a view of the end of a perforated box or channel; and Fig. 9 is a cross-section of such 50 a chamber provided with a rib d .

Similar letters refer to similar parts throughout.

Near the steam-boiler A is the inlet I for fresh air to the heating-piping K, which leads the air first through the fume-channel B, between the steam-boiler and the chimney D, then through the one side flue L, the smoke-chamber M, and the other side flue L of the steam-boiler to the blower G. On the way 55 through the whole course of the piping K the air will become heated, so that it arrives with a very high temperature at the blower G.

H denotes some suitable injecting device of any known construction for introducing a regulated quantity of liquid or gaseous fuel 60 or superheated steam into the hot air. In case liquid fuel is introduced the injecting device is so arranged that it will divide the liquid fuel finely and distribute it evenly in the air-supply. After the mixture of hot air 65 and fuel or superheated steam has entered the blower G it will be discharged by the latter under a certain pressure into the main pipe C and the side branches N, leading to the chambers P of the fire-grates Q Q. Here the 70 mixture is distributed into the perforated pipes a of Fig. 3, or the perforated boxes or channels b of Fig. 4, or the perforated pipes a of Figs. 5 to 7, as the case may be, and from 75 there pressed out through the holes o in 80 streams through the fire, as indicated approximately by the dotted lines in Figs. 3 to 5. Owing to the high temperature and highly-inflammable character of the mixture, it will be ignited immediately and increase the heat 85 of the fire. Owing to its pressure it will be able to force its way through the layer of burning and glowing coals, and thereby prevent the coals and slag-cinders from jamming 90 and cooling down. For the same reason the mixture will also assist in utilizing low-grade coals by keeping the temperature high and penetrating the coals everywhere.

As already mentioned above, the fire-grates 95 Q Q may be constructed in either of the manners illustrated by Figs. 3 to 9. The front ends of the perforated pipes a or boxes or channels b may rest in suitable cuts of the front plate k . The pipes a or boxes b may be in two halves united by suitable sleeves l or 100

other means, or they may be made in one piece for the whole length. Their closed back ends may be fitted into suitable holes of the angle-piece *m*, or they may be supported 5 in some other manner.

v v denote common fire-bars placed between the pipes *a* or boxes.

Fig. 9 shows an example of how a perforated box may be stiffened by a rib *d*.

10 The blower *G* is assumed to be driven from a steam-engine *E* by means of a counter-shaft *F*. It may, however, be driven from an electromotor, a shafting, or otherwise. It may also be replaced by a compressor, so as to attain 15 a higher pressure of the mixture on entering the fires.

The injecting device *H* may be arranged for regulating the quantity of liquid or gaseous liquid or superheated steam at pleasure, 20 and thus attaining a mixture the parts of which are in some suitable proportions to each other.

The arrangement as described and shown may be applied to any furnace. The superheated steam may be produced in a piping similar to the piping *K* and conducted in a similar manner from the steam-generator to the injecting device *II*.

I declare that what I claim as my invention, and desire to secure by Letters Patent, 30 is—

1. In a smoke-consuming furnace the combination with an inlet for fresh air, of an air-heating piping laid in the fume-channel of 35 chimney and in the flues of furnace, a blower attached to the end of said heating-piping, an injecting device placed on the junction between said heating-piping and said blower and arranged for introducing liquid or gaseous fuel or superheated steam, a series of perforated pipes replacing several or all the fire-bars and distributing the compressed mixture of hot air and fuel or superheated steam into 40 the fire, and a piping between said blower and said perforated pipes, substantially as set forth.

2. In a smoke-consuming furnace, the combination with an inlet for fresh air, of an air-heating piping laid in the fume-channel of 45 chimney and in the flues of furnace, a blower

attached to the end of said heating-piping, means for driving said blower, an injecting device placed at the junction between said heating-piping and said blower and arranged for introducing liquid or gaseous fuel or superheated steam, a series of perforated pipes or boxes replacing several or all the fire-bars and distributing the compressed mixture of hot air and fuel or superheated steam into the fire, and a piping between said blower and 55 said perforated pipes or boxes, substantially as set forth.

3. In a smoke-consuming furnace the combination with an inlet for fresh air, of an air-heating piping laid in the fume-channel of 60 chimney and in the flues of furnace, a compressor attached to the end of said heating-piping, an injecting device placed at the junction between said heating-piping and said compressor and arranged for introducing liquid or gaseous fuel or superheated steam, a series of perforated pipes or boxes replacing several or all the fire-bars and distributing the compressed mixture of hot air and fuel or superheated steam into the fire, and a piping 65 between said compressor and said perforated pipes or boxes, substantially as set forth.

4. In a smoke-consuming furnace the combination with an inlet for fresh air, of an air-heating piping laid in the fume-channel of 70 chimney and in the flues of furnace, a compressor attached to the end of said heating-piping, means for driving said compressor, an injecting device placed at the junction between said heating-piping and said compressor and arranged for introducing liquid or gaseous fuel or superheated steam, a series of perforated pipes or boxes replacing several or all the fire-bars and distributing the compressed mixture of hot air and fuel or superheated steam into the fire, and a piping 75 between said compressor and said perforated pipes or boxes, substantially as set forth.

In witness whereof I have hereunto signed my name in the presence of two subscribing 80 witnesses.

PAUL CORNELIUS.
